UNITED STATES PATENT OFFICE.

BYERS W. KADEL, OF BALTIMORE, MARYLAND, ASSIGNOR TO THE SYMINGTON COMPANY, OF NEW YORK, N. Y., A CORPORATION OF MARYLAND.

DRAFT RIGGING.

Application filed February 24, 1925. Serial No. 11,239.

This invention relates to draft rigging for railway cars and more particularly to mechanism for operatively connecting the coupler, yoke member and draft sills and permitting a desired amount of pivotal motion between the coupler and yoke member.

One of the principal features of my invention generally considered, is to provide a pivotal connection between a yoke and coupler employing a vertical key therebetween, said key being supported by means of a small horizontal cross key which also serves to guide the rear end of the coupler.

An object of the invention is to provide a connection between a coupler and yoke in a railway draft rigging, the coupler being provided with a vertical slot and the yoke provided with registering vertical slots in its forwardly extending arms, all of said slots being longitudinally extended with a vertical key passing therebetween, and supporting means provided for said key.

Another object of my invention is the provision of a novel form of railway draft rigging in which a yoke of the vertical type is provided and formed with rearwardly flaring vertical slots through the forward ends of the arms thereof, the coupler stem being embraced by said arms, and a vertical key inserted through the slots in the arms and a corresponding slot in the coupler stem whereby pivotal motion between said coupler and yoke is provided by virtue of the flaring slots in the yoke.

Another object of my invention is the provision of a novel form of railway draft rigging in which a slotted coupler is pivotally connected to a vertical yoke by means of a vertical key extending through corresponding slots in the yoke and coupler, the slots in the yoke being rearwardly flaring to allow for angling of the key therein and thereby permit pivotal motion of the coupler with respect thereto, and a slotted follower provided between the rear of the coupler and cushioning mechanism whereby buffing forces are transmitted from the coupler to said mechanism, said follower being slidably supported with respect to the draft sills by means of a substantially horizontal key extending through the slot thereof.

A further object of my invention is the provision of a pivotal connection between the coupler and yoke members of a railway draft rigging, said pivoting being accomplished by

means of a vertical key therebetween supported on a horizontal key through the coupler and draft sills, the portions of the yoke where said vertical key passes therethrough being thickened for increasing the bearing area therebetween and flared rearwardly for allowing angling therein, a slotted follower being provided to the rear of said coupler between the same and cushioning mechanism, said follower being supported on a substantially horizontal key passing therethrough, which key carries a plurality of spacing washers for centering said follower and spacing the same from the cheek plates and center sills.

Other features of the invention consisting in the construction of the several elements, together with their particular arrangement and combination, will become apparent as the description proceeds.

In the drawings illustrating my invention, the scope whereof is pointed out in the claims:

Figure 1 is a horizontal sectional view of draft rigging embodying my invention.

Figure 2 is a side elevation with parts in vertical longitudinal section.

Referring to the drawings in which similar reference characters serve to designate corresponding parts in the several views, I have shown a coupler 3 connected to a yoke 4 by means of a vertical key 5. For supporting the key 5 as well as the coupler 3 and forward end of the yoke 4, a horizontal key 6 extending through the slot 7 in the coupler and slots 8 and 9 in the yoke is also provided. It will be noted that this key 6 extends between the center or draft sills 11 and cheek plates 12 which may be rigidly attached thereto, said key extending through slots 13 in said cheek plates.

The vertical key connecting the coupler and yoke members extends through a slot 14 in said coupler stem with a relatively small amount of play therein. The corresponding slots 15 and 16 in the yoke arms 17 and 18, respectively, are preferably formed with their forward ends in substantial alignment with the forward end of the slot 14, the side walls of said slots, however, flaring outwardly to the rear and said slots being slightly longer than the slot 14, thereby allowing more play between them and the key 5 as well as permitting an angling of said key therein. By reason of the angling permitted between the key 5 and the slots 15 and 16, it will be apparent that the coupler 3 connected to said yoke by

means of the key 5 is permitted to pivot or angle to a corresponding degree with respect to the yoke 4.

The upright or vertical key 5 is intersected by and supported upon the horizontal key 6 but an additional supporting means may be provided in the form of a carry iron 19 positioned thereunder and supported from the center sills by means of bolts, as illustrated in the drawing. This carry iron may serve as an additional support for the forward end of the yoke. The forward end of the coupler may be slidably supported, if desired, upon a carry iron 21, as is usual.

15 The rear end of the yoke may be adapted to abut against the back stop 22 and a rearwardly disposed carry iron 23 may also be provided. The rear portion of the coupler stem 24 is preferably cored at 25 and the rear surface crowned, as illustrated in Figure 1, to lighten the weight thereof, and increased in depth or provided with top and bottom lugs at the extreme end to serve for spacing the arms of the yoke. Abutting against the rear face of the coupler stem is a follower block 26 upon which the coupler is adapted to rock by virtue of the crowned or curved rear portion thereof. The block 26 is slotted at 27 for receiving a substantially horizontal key 28 which extends between the center sills 11 and cheek plates 12 thereon through slots 29 therein. The slots 29 are preferably alined with the slots 13 and both sets may be extended through corresponding slots in the draft sills.

30 The key 28 preferably carries a plurality of spacing washers 31 which serve to center the follower 26 and space it from the cheek plates 12. The follower 26 is centered vertically by being embraced by the forwardly extending arms 17 and 18 of the yoke. Cushioning mechanism illustrated diagrammatically by dot and dash lines in Figure 2, is provided between the rearward face of the follower 26 and the loop portion of the yoke member, as is usual.

45 The arms 17 and 18 where the same are pierced by the slots 15 and 16, are preferably thickened, as shown at 32 and 33 whereby a greater bearing area between said arms and the vertical key 5 is provided.

50 By virtue of the foregoing construction I have provided a novel and efficient pivotal connection between the coupler and yoke members for railway draft rigging. Although the slots 8 and 9 in the present construction need only be long enough to receive the small cross key 6 yet they are preferably made approximately eight and three-quarter inches long to take a standard key and allow for the standard amount of movement in the cushioning mechanism.

55 When draft forces are applied to the coupler they are transmitted first to the vertical key and then directly to the thickened por-

tions 32 and 33 of the yoke arms. The yoke carries these draft forces to the cushioning mechanism which in turn transmits it to the follower 26, key 28 and from thence to the cheek plates and center sills. When buffing 70 forces, however, are applied to the coupler, the key 5 is relieved of substantially all such forces as the same are transmitted directly to the follower 26, through the cushioning mechanism and from thence through the loop 75 portion of the yoke to the back stop 22. The spring washers 31 preferably are not as long as the follower 26 and therefore do not contact with the cushioning mechanism and affect the transmission of forces with respect 80 thereto.

Having now described my invention, what I claim as new and desire to secure by Letters Patent, is:

1. In a railway draft rigging, the combination with a coupler, of a yoke, means pivotally connecting said coupler and yoke and serving to transmit draft forces therebetween, means extending at an angle to, intersecting and supporting said connecting means to align 90 said coupler and yoke, cushioning mechanism, a slotted follower between the rear of said coupler and said cushioning mechanism, and means supporting said follower.

2. In a railway draft rigging, the combination with a coupler having a stem provided with a plurality of intersecting longitudinally disposed slots, of a yoke provided with a four-walled extension surrounding the coupler stem and pierced by longitudinal slots complementary to and registering with said coupler slots, means extending through one of said coupler slots and the registering yoke slots for connecting said coupler and yoke, and means extending through the other coupler slot and the registering yoke slots, intersecting and supporting the first means for supporting said coupler and yoke.

3. In a railway draft rigging, the combination with a coupler having a stem provided with a plurality of intersecting longitudinal slots, of a yoke provided with a four-walled extension surrounding the coupler stem and pierced by longitudinal slots complementary to and registering with said coupler slots, means extending through one of said coupler slots and the registering yoke slots for connecting the coupler and yoke, means extending through the other coupler slot and registering yoke slots, intersecting 120 and supporting the first means for supporting said coupler and yoke, cushioning mechanism to the rear of said coupler, a slotted follower between said coupler and cushioning mechanism, and means supporting said follower.

4. In a railway draft rigging, the combination with center sills, of a coupler, a yoke, means pivotally connecting said coupler and yoke and serving to transfer draft forces therebetween, means extending substantially 130

at right angles to, intersecting and supporting said connecting means to aline said coupler and yoke, cushioning mechanism, a slotted follower between the rear of said coupler and cushioning mechanism, and means supporting said follower and serving to transmit draft forces between it and the center sills.

5. In a railway draft rigging, the combination with center sills, of a coupler, a yoke, vertically disposed means pivotally connecting said coupler and yoke and serving to transmit draft forces therebetween, means extending substantially horizontally, intersecting and supporting said connecting means to aline said coupler and yoke, cushioning mechanism, a slotted follower between the rear of said coupler and cushioning mechanism, a substantially horizontal key passing through the follower slot for supporting the same and transmitting draft forces between it and the center sills, and means carried by said key for spacing said follower between the center sills.

25. 6. In a railway draft rigging, the combination with center sills, of a coupler, a yoke, pivotal and draft force transmitting means therebetween, means intersecting said coupler and yoke to aline the same, cushioning mechanism, a slotted follower between said cushioning mechanism and the rear end of the coupler, and a key operatively connecting said follower to the center sills.

35. 7. In a railway draft rigging, the combination with a slotted coupler, of a yoke with forwardly extending arms embracing the rear end of the coupler, said arms being formed with longitudinal rearwardly flaring slots registering with a coupler slot, a key extending through said yoke and coupler slots serving to transmit draft forces and allowing pivotal motion between said coupler and yoke, and means intersecting said key for supporting the same and said coupler and yoke.

40. 8. In a railway draft rigging, the combination with a slotted coupler, of a yoke of the vertical hooded type with forwardly extending arms embracing the rear end of the coupler, said arms being formed with longitudinal rearwardly flaring slots registering with a coupler slot, a vertical key extending through said yoke and coupler slot serving to transmit draft forces and allowing pivotal motion between said coupler and yoke, and means for supporting said key, extending through the hood of the yoke and the coupler for supporting and alining the same.

45. 9. In a railway draft rigging, the combination with a slotted coupler, of a yoke of the vertical type with forwardly extending arms embracing the rear portion of the coupler, said arms being formed with longitudinal rearwardly flaring slots registering with a coupler slot and provided on their forward

ends with integral side walls, a vertical key extending through said yoke and coupler slots serving to transmit draft forces and allowing pivotal motion between said coupler and yoke, and a horizontal key extending through another slot in the coupler at an angle to the first key and intersecting said vertical key and the side walls of the yoke for supporting the coupler, yoke and vertical key.

10. In a railway draft rigging, the combination with center sills, of a slotted coupler, a yoke with forwardly extending arms embracing the coupler stem, said arms being formed with longitudinal slots increasing in width from front to rear and registering with a coupler slot, a key extending through said yoke and coupler slots, serving to transmit draft forces and allowing pivotal motion between said coupler and yoke, supporting means intersecting said key and sills, cushioning mechanism positioned to the rear of said coupler, a slotted follower for transmitting draft forces from said cushioning mechanism, and connecting means between said follower and center sills for transmitting draft forces thereto.

11. In a railway draft rigging, the combination with center sills with cheek plates connected thereto, of a slotted coupler, a yoke of the vertical type with forwardly extending arms embracing the stem of the coupler, said arms being formed with longitudinal rearwardly flaring slots registering with a coupler slot and provided with integral side walls, a vertical key extending through said yoke and coupler slots serving to transmit draft forces and allowing pivotal motion between said coupler and yoke, a horizontal key extending through another slot in the coupler at an angle to the first slot, intersecting said vertical key and the side walls of the yoke for supporting said coupler, yoke and vertical key, cushioning mechanism to the rear of said coupler, a slotted follower between said coupler and cushioning mechanism for transmitting buffing forces therebetween, and a horizontal key extending through the slot in the follower and said cheek plates for transmitting draft forces from the cushioning mechanism to the center sills.

12. In a railway draft rigging, the combination with center sills with cheek plates connected thereto, of a slotted coupler, a yoke of the vertical type with forwardly extending arms embracing the stem of the coupler, said arms being formed with longitudinal rearwardly flaring slots registering with a coupler slot and provided with integral side walls, a vertical key extending through said yoke and coupler slots serving to transmit draft forces and allowing pivotal motion between said coupler and yoke, a horizontal key extending through another slot in the coupler at an angle to the first slot, intersecting said ver-

tical key and the side walls of the yoke for supporting said coupler, yoke and vertical key, cushioning mechanism to the rear of said coupler, a slotted follower between said coupler and cushioning mechanism for transmitting buffing forces therebetween, a horizontal key extending through the slot in the follower and said cheek plates for transmitting draft forces from the cushioning mechanism to the 10 center sills, and spacing washers positioned on said horizontal key for centering said follower and spacing it from the cheek plates.

13. In a railway draft rigging, the combination with slotted center sills, of cheek plates 15 connected thereto, said plates being each provided with a plurality of spaced slots therethrough, the corresponding slot of each cheek plate being transversely alined with that of the other, a coupler, a yoke, a key passing 20 through a pair of alined cheek plate slots and through said coupler and yoke, an upright key for operatively connecting the coupler yoke, said upright key being supported on said key between the cheek plates, cushioning mechanism 25 within said yoke, means interposed between said mechanism and said coupler for transmitting buffing forces therebetween, and another key passing through said means and another pair of alined cheek plate slots for operatively connecting said means and cheek plates.

14. In a draft rigging, the combination with cheek plates each provided with a plurality of longitudinally spaced slots there- 35 through, the slots in one being substantially alined transversely with those in the other, of a coupler, a yoke, means passing through a pair of alined slots and intersecting said coupler and yoke for supporting the same, a vertical key supported on said means and intersecting said coupler and yoke for transmitting draft forces between the coupler and yoke and permitting the coupler to pivot with respect to the yoke, cushioning mechanism operative- 40 45 ly associated with said yoke, means intermediate said mechanism and coupler for transmitting forces therebetween, and means intersecting said intermediate means and passing through another pair of alined cheek plate 50 slots for transmitting forces from the cushioning mechanism to the cheek plates.

15. In a railway draft rigging, the combination with a coupler having a stem provided with a plurality of intersecting longitudinally disposed slots, of a yoke provided with a four-walled extension surrounding the coupler stem and pierced by longitudinal slots complementary to and registering with said coupler slots, means extending through one of said coupler slots and the registering yoke slots for pivotally connecting said coupler and yoke, and means extending through the other coupler slot and the registering yoke slots. 60

16. A coupler provided with an upright longitudinally extending slot through the 65 stem thereof, adapted for receiving a pivoting key and a substantially horizontal longitudinally extending slot intersecting said upright slot for receiving a supporting key, the extreme end of said stem being formed with top 70 and bottom lugs.

17. A coupler provided with a vertical longitudinally extending slot through the stem thereof for receiving a pivoting key, and a horizontal longitudinally extending slot in 75 intersecting said vertical slot for receiving a horizontal key for supporting the coupler stem and the vertical key, the rear of said stem being crowned for rocking engagement with an adjacent member. 80

18. A yoke for railway draft rigging with forwardly extending arms provided with longitudinally extending rearwardly flaring registering slots, and bridge portions connecting the sides of the arms and also provided with longitudinally extending registering slots, 85 said latter slots being longitudinally offset with respect to the former slots.

19. A vertical yoke for railway draft rigging with forwardly extending arms, the ends 90 of which are thickened and provided with longitudinally extending registering slots through said thickened ends for receiving a draft force transmitting key therethrough, and upright integral bridge portions connecting the sides of said arms and provided with longitudinally extending registering slots for simultaneously receiving a substantially horizontal key for supporting said yoke. 95

In testimony whereof I affix my signature.
